[57] CLAIM

The ornamental design for the eye structure for blow molded yard figures, as shown and described.

DESCRIPTION

FIG. 2 is a front elevational view thereof;
FIG. 3 is a right side elevational view thereof, the left side being substantially identical; and,
FIG. 4 is a top plan view thereof.
